CLAIM

The ornamental design for a gemstone jewelry article, as shown and described.

DESCRIPTION

FIG. 1 is a side and bottom perspective view of a gemstone jewelry article showing my new design;

FIG. 2 is a side perspective view of the gemstone jewelry article with the top gemstone portion in a flexed position;

FIG. 3 is a side view of gemstone jewelry article;

FIG. 4 is a side view of the gemstone jewelry article with the top gemstone portion in a flexed position;

FIG. 5 is a front view of the gemstone jewelry article;

FIG. 6 is a front view of the gemstone jewelry article with the top gemstone portion in a flexed position;

FIG. 7 is a front view of the gemstone jewelry article with the top gemstone portion in a flexed S position;

FIG. 8 is a top view of the gemstone jewelry article;

FIG. 9 is a top view of the gemstone jewelry article with the top gemstone portion in a flexed position;

FIG. 10 is a top view of the gemstone jewelry article with the top gemstone portion in a flexed S position;

FIG. 11 is a bottom view of the gemstone jewelry article;

FIG. 12 is a bottom view of the gemstone jewelry article with the top gemstone portion in a flexed position; and,

FIG. 13 is a bottom view of the gemstone jewelry article with the top gemstone portion in a flexed S position.

The broken lines shown in the figures represent portions of the gemstone jewelry article which form no part of the claimed design.

1 Claim, 3 Drawing Sheets
